[57] ABSTRACT

A lighting unit comprising a box-like housing open at one face thereof, a light reflector having inner reflective surfaces, outer reflective surfaces and reflective side surfaces interconnecting adjacent inner and outer surfaces to define a plurality of spaced recesses, and mounting means within each recess for supporting a light source therein.

LIGHTING UNIT AND REFLECTOR THEREFOR

This invention relates to a lighting unit and particularly but not exclusively to such a unit incorporating a plurality of fluorescent tubes.

Many forms of lighting units incorporating one or more fluorescent tubes have previously been proposed and in many cases lighting unit housings have been provided with reflectors. Such reflectors however are normally fixedly secured to the housing and the necessary electrical power supply wiring connections for the tube or tubes are visible at all times.

An object of the present invention is to provide a lighting unit capable of incorporating a bank of fluorescent tubes and which is easy to assemble or dismantle and which is inexpensive to manufacture.

According to the present invention there is provided a lighting unit comprising a box-like housing open at one face thereof, a light reflector having inner reflective surfaces, outer reflective surfaces and reflective side surfaces interconnecting adjacent inner and outer surfaces to define a plurality of spaced recesses, and mounting means within each recess for supporting a light source therein.

An embodiment of the present invention will now be described, by way of example, with reference to the accompanying drawings in which:

FIG. 1 is a perspective view of one form of lighting unit; and

FIG. 2 is a sectional view on an enlarged scale on the line II-II of FIG. 1.

Referring to the drawings, a lighting unit comprises a flat box-like housing relatively narrow in depth and made up of a back wall 3, side walls 4 and end walls 5. The box-like structure is open on the front face thereof, the opening being bounded by an inwardly directed peripheral flange 6 extending from each of the side and end walls 4 and 5 respectively.

Positioned within the housing is an aluminium reflector 7 polished over its whole surface area and corrugated so as to form a series of flat inner surfaces 8 and parallel flat outer surfaces 9 interconnected by angled diverging side wall portions 10. A series of spaced recesses 11 is thus formed by each inner surface 8 and its adjacent side wall portion 10. As shown in FIG. 2, a pair of flexible spring clips 12 for securing a fluorescent tube 13 is fixedly mounted on each of the inner surfaces 8 of the reflector.

The reflector 7 is flexible and is sprung into position within the housing to close the open face thereof and is retained in position by the inwardly directed flanges on the side walls 4 of the housing. The necessary well-

known electrical wiring connections for controlling electric power supply to the tubes are led to the ends of the fluorescent tubes in normal manner through either the end walls 5 of the back wall 3 of the housing.

5 The electrical connections to the tubes are then concealed by the insertion of corrugated end closure plates 14 which are also of polished aluminium and which, as shown in FIG. 2, have flat outer surfaces 15 designed to abut against the outer surfaces 9 of the reflector 7 and flat inner surfaces 16 which lie within the recesses 11 and parallel to but spaced from the inner surfaces 8 of the reflector 7 to define compartments in which the electrical connections are contained but concealed from external view.

10 15 In the same manner as the flexible reflector 7, the corrugated closure plates 14 are sprung into position in the housing to be retained by the flanges 6 on the side and end walls 4 and 5 respectively.

The depth of the recesses 11 formed in the reflector 7 is such that the fluorescent tube located in each is housed wholly within its recess and no part of the tube projects outwardly beyond the outer flat surfaces 9 of reflector 7. In this way the amount of light from a given light source reflected by the reflector 7 to a desired location has been found to be satisfactorily high. In addition, a bank of fluorescent tubes in a lighting unit as illustrated in the drawings is visually pleasing when lit.

Although in the above described embodiment, fluorescent tubes are referred to as the light source, it will be readily apparent that other forms of light source such as electric bulbs can equally well be used. In addition the various dimensions of the reflective surfaces of the reflector can be varied to suit requirements.

What is claimed is:

1. A lighting unit comprising a box-like housing open at one face thereof, a corrugated light reflector located within said housing so as to define a plurality of light source-receiving recesses, said reflector being light-reflective over substantially the full extent of the outer face thereof, and a corrugated closure plate, having an outer light-reflective surface, located adjacent each end of the reflector, each said closure plate nesting within the reflector to define a compartment within which electrical light-source connections can be concealed.

2. A lighting unit as claimed in claim 1, in which a peripheral flange is provided around the open face of the housing, and the reflector and closure plates are flexible to enable insertion into the open face of the housing for retention therein by said peripheral flange.
